J. CHAB.
HOISTING HOOK.
APPLICATION FILED APR. 14, 1915.

1,150,500.

Patented Aug. 17, 1915.

UNITED STATES PATENT OFFICE.

JOSEPH CHAB, OF DORCHESTER, NEBRASKA.

HOISTING-HOOK.

1,150,500.

Specification of Letters Patent. Patented Aug. 17, 1915.

Application filed April 14, 1915. Serial No. 21,359.

To all whom it may concern:

Be it known that I, JOSEPH CHAB, a citizen of the United States of America, residing at Dorchester, in the county of Saline 5 and State of Nebraska, have invented certain new and useful Improvements in Hoisting-Hooks, of which the following is a specification.

The invention relates to an improvement 10 in hoisting hooks, and particularly to a hoisting hook of the type adapted for control from a more or less remote point to release the element carried by the hook, whereby the load may be automatically released 15 or dropped at any desired point.

The invention is designed to provide a hoisting hook in which the jaws are locked in closed relation through the medium of a spring pressed bolt, adapted for manual operation, the longitudinal movement of the bolt releasing the jaws to permit opening of the same to release the load connected element, the bolt in fully retracted position operating to hold the doors open until the 25 load connected element is replaced therein, whereupon the jaws are forced to a closed position and automatically locked in such position by the bolt.

The invention in its preferred form of 30 details will be described in the following specification, reference being had particularly to the accompanying drawings, in which:

Figure 1 is a perspective view of the improved releasing hook; Fig. 2 is a plan of the same with the cover plate removed, and the parts being shown in locked or operative position. Fig. 3 is a similar view with the parts shown in a released position.

The improved hoisting hook is constructed to provide a base portion 1, which has an inner surface to provide for the reception of the moving parts of the hook. In forming the base 1 to accommodate the moving parts said inner surface of the base is cut out or channeled to provide a longitudinally extending throat 2 arranged centrally and longitudinally of the base, the lower end of the throat communicating with 50 a recess 3, coextensive with the width of the base and extending to the lower edge thereof, said recess being provided for the reception of the jaws hereinafter referred to. Above the recess 3 the throat 2 is laterally 55 enlarged, on each side, as at 4, to provide spring recesses, and immediately above the

enlargement the throat proper is of increased width as at 5 for a portion of its upper length, as clearly shown in Figs. 2 and 3. As thus constructed the relatively 60 inner surface of the base is in effect formed with side abutments 6, the proximate edges of which, as well as the lower edges, are shaped to provide the throat, recess, and various enlargements, and while it is contemplated that the parts be constructed of an integral member, so far as the base is concerned it is obvious that if desired the abutments 6 may be of separate features, with their edges appropriately formed, and 65 secured to the base, which under some circumstances would comprise a comparatively thin plate. A cover plate 7 is designed to close over the formed side of the base, so that with the cover plate in place the various recesses, throat portions and the like are 70 closed, to completely house the working parts.

Pivots mounted in the recess 3, preferably on pivot pins extending through the 80 base and cover plate are jaws 8 rounded on their outer edges, and formed on their inner edges with a rounded inwardly extending semi-circular recess 9, and above said recess with a cut away portion 10. The construction of the jaws and their pivotal support is such that when said jaws are in locking position the recesses 9 form a circular receiving opening while the cut-away portions 10 present a channel corresponding in 90 width to and disposed in alignment with the throat 2. The material of each jaw intermediate the recess 9 and cut-away portion 10 provides a projection 11, the said projections forming the bottom wall of the channel referred to.

Mounted for movement in the throat 2 is a locking bolt 12, which bolt is formed at its lower end with an enlarged locking nose 13. The relatively upper end of the bolt is 100 formed with offset projections 14 which slidably operate in the enlarged portion 5 of the throat, the engagement between the upper walls of which enlargement and the projections 14 serve to limit the upper movement of the bolt. The nose 13 fits the lower portion of the throat and the channel formed by the cut-away portions 10 of the jaws, so that when the nose is in normal position, that is within the channel, the jaws are prevented from outward swing on their pivots, 110 that is locked in closed position. The

relative disposition of the projections 14 and upper walls of the portion 5 of the throat is such as to permit an upward movement of the locking bolt to an extent to 5 withdraw the nose 13 from the channel, thereby permitting free movements of the jaws.

To exert a normal tendency to move the locking bolt to its operative or locking position I arrange leaf springs 15 in the rounded enlargements 4 of the throat, the lower ends of the springs bearing against the nose 13 and the upper ends fitting in notches 16 in the walls of the enlargement. The base 15 member and cover plate are cut out at their lower and upper ends as at 17 and 18 to permit movement of the load connected element 19 into and out of the jaws, and to permit the application of an operating member as 20 to the upper end of the locking bolt 12. The hook as an entirety is formed with openings 21, preferably in the upper portion, to receive a supporting cable or rope 22, the operating member 20 of the locking 25 bolt being in the form of a rope or the like which may be extended in any convenient form. Assuming the element 19 in the hook and the jaws thereof locked to hold the element in place, it is obvious that so long as 30 the nose 13 of the locking bolt fits in the channel formed by the jaws, said jaws cannot open to release the element. When it is desired to release said element and drop the load, the operating member 20 is drawn 35 upon to move the bolt upwardly, and as soon as the nose 13 leaves the channel of the jaws, the latter, under the weight of the load will spread to release the load-connected element. As the jaws open their upper edges ride 40 beneath the lower edge of the nose 13 and the latter under the tension of the spring 15 will exert sufficient pressure on the upper edges of the jaws to hold them open. When it is desired to again connect the element 19 45 the latter is forced between the lower ends of the jaws and up and into contact with the projections 11, which contact tends to

move the lower ends of the jaws into closed relation. The movement is continued until the usual channel is presented for the reception of the nose of the bolt, whereupon said nose is snapped into the channel and the jaws are locked in closed relation.

From the above description and drawings it will be obvious that I have provided a 55 hoisting hook from which the load may be automatically released at any time and from any conveniently remote point, the parts involved being few in number and of exceedingly simple construction and arrangement, 60 disposed notwithstanding for rigidity and strength of structure and certainty of operation under all working conditions.

What is claimed is:

1. A hoisting hook including a base, jaws 65 pivotally mounted on the base, the upper ends of the jaws being formed to together present a channel, a locking bolt slidably mounted in the base, and means normally projecting said bolt into said channel.

2. A hoisting hook including a base formed with a throat, jaws pivotally mounted in the base and formed to together present a channel, a locking bolt slidably mounted in the throat and adapted to fit 75 within the channel when the jaws are in closed relation, and springs mounted in the base and bearing on the bolt.

3. A hoisting hook including a base formed with a throat, jaws pivotally mounted in the base and formed to together present a channel, a locking bolt slidably mounted in the throat and adapted to fit 80 within the channel when the jaws are in closed relation, and springs mounted in the 85 base and bearing on the bolt, and a cover plate secured to the base and housing the parts.

In testimony whereof I affix my signature in presence of two witnesses.

JOSEPH CHAB.
